UNITED STATES PATENT OFFICE.

JOSEPH B. SARGENT, OF NEW HAVEN, CONNECTICUT.

DESIGN FOR CHANDELIER-HOOK.

Specification forming part of Design No. 5,818, dated April 23, 1872.

To all whom it may concern:

Be it known that I, JOSEPH B. SARGENT, of New Haven, in the county of New Haven and State of Connecticut, have invented a new Design for Chandelier-Hook; and I do hereby declare the following, when taken in connection with the accompanying drawing and the letters of reference marked thereon, to be a full, clear, and exact description of the same, and which said drawing constitutes part of this specification, and represents a side view.

This invention relates to a design for a hook, such as are screwed into the ceiling to support hanging lamps or chandeliers, and commonly called chandelier-hooks; and consists in a hook flat upon its sides, the sides paneled by a

raised edge, and ornamented by tracery, as shown in the accompanying illustration.

The hook is made flat upon its two sides, and cast with a raised edge, *a*, which gives to the sides the form of a panel, the surface of which panel is, by preference, matted and the edge polished, and the surface of the panel ornamented by tracery cast thereon, as shown.

I claim as my invention—

The design for chandelier-hook, as herein described and shown in the accompanying illustration.

J. B. SARGENT.
